UNITED STATES PATENT OFFICE.

JOHN H. KING, OF CINCINNATI, OHIO, ASSIGNOR OF ONE-HALF TO EDWARD I. ROBINSON, OF SAME PLACE.

BRAKE FOR STREET-CARS.

SPECIFICATION forming part of Letters Patent No. 448,438, dated March 17, 1891.

Application filed December 26, 1890. Serial No. 375,784. (No model.)

To all whom it may concern:

Be it known that I, JOHN H. KING, a citizen of the United States, and a resident of Cincinnati, in the county of Hamilton and 5 State of Ohio, have invented certain new and useful Improvements in Brakes for Street-Cars, of which the following is a specification.

My invention is an improved street-car 10 brake. It is especially adapted for electric street-cars. In cars of this class a great deal of the space under the car is occupied by the motor and the gearing which transmits the power from it to revolve the axles, which renders it difficult to apply the ordinary brakes 15 so as to make them effective.

The object of my invention is to provide a compact device whereby the momentum of the car may be utilized to rapidly and forc- 20 ibly apply the brakes.

The invention will be first fully described in connection with the accompanying drawings, and will then be particularly referred to, and pointed out in the claims.

25 Referring to the drawings, in which like parts are indicated by similar reference-letters wherever they occur throughout the various views, Figure 1 is a longitudinal vertical sectional view of part of a car-platform provided 30 with my improvements. Fig. 2 is a detail view, in vertical section, through line $x-x$ of Fig. 1, upon a greatly enlarged scale, of the mechanism for actuating the brake. Fig. 3 is a vertical transverse section taken through line $y-y$ of Fig. 2. Fig. 4 is a view, partly in side 35 elevation and partly in vertical section, of a modified form of clamp for holding the brake after it is thrown on. Fig. 5 is a detail plan view, upon an enlarged scale, of the same.

40 Referring to the parts, A is a portion of the car-frame; B, the wheels; B', the axles, and C the brake-shoes. These parts are constructed in the usual manner, and need not, therefore, be specifically described.

45 As there is only about seven inches of space in electric cars between the casing which encloses the electric motor and the axle-boxes, the brakes must be arranged upon each side of the car, one to be used when the car is proceeding in one direction and the other when 50 the car is proceeding in the opposite direction,

the rear brake-retaining device being rendered inactive in each case. As both ends of the car are fitted alike and are duplicates of each other, I have only shown one side of the car 55 as fitted with the brake, which I will now proceed to describe.

Upon the axles B is fitted a friction-roll D. It is made in two parts to embrace the axle. The axle and the half parts of the pulley are 60 bored to receive pins d, which prevent the roll D from turning independent of the axle. The halves of the roll D are cored out centrally to receive the links d', that are let into them and held in position by pins d² to steady 65 the halves in position; or, instead of this arrangement, the halves may be bolted together or pins placed through them outside of the axle to keep them in alignment.

The roll D has tubular extensions d³ upon 70 each side, over which are fitted the standards or bearings E, which are also divided to fit over the journal-extensions d³, and are fastened by bolts d⁴ passing through outwardly-projecting flanges d⁵. On the upper ends of 75 these standards is journaled the bearings f of the eccentric roll F, which roll carries the yoke G, in the lower ends of which are journaled friction-rolls H. Upon the extended shaft of the eccentric F is secured a crank F', 80 the lower end of which is connected to the brake-staff I by a brake-rod i and chain i'. Upon the opposite axle is fitted a box J, which is also in two parts and clamped around the axle which revolves freely within it. This 85 box has a projecting lug j corresponding to a similar lug which projects from the standard E. A channel-iron bar K has its opposite ends secured firmly upon the lugs j e, and serves the double purpose of holding the 90 standards E rigidly and furnishing the support for the brake-lever L, which is fulcrumed upon a stud l, projecting from a hanger l', which is bolted to and depends down from the under side of the bar K. The brake-rods 95 M M' are connected to the brake-beam and the lever L in the usual manner.

N is a board of hard wood, one end of which is connected to the upper end of the brake-lever by a strap-box n. This board passes 100 freely between the friction-rolls D and H when the rolls H are in the position shown in

the drawings; but when the eccentric F is partially rotated by winding the chain i' around the brake-staff I the yoke G is depressed, forcing the rolls H down upon the top of the board N, clamping it firmly between the friction-rolls, by which it will be carried forward to throw on the brakes. After the brakes are thrown on, which will require but a slight turn of the brake-staff, the chain is released 5 and the board held in its forward position by the piston and cylinder shown in Fig. 1 or by means illustrated in Figs. 4 and 5.

The means for holding the brake on, as shown in Fig. 1, will be first described. O is 10 a cylinder suspended underneath the end of the car and fitted with a piston P. The piston and board N are connected by the rod Q. The cylinder is fitted at one end with an outwardly-opening check-valve o and a spring- 15 pressed inwardly-opening valve o'. The stem of the valve o' projects up through the floor of the car and is fitted with a head or cap o², which, when pressed down by the foot of the driver, opens the valve and equalizes the air-pressure 20 upon both sides of the piston P. Now when the board is carried forward by the friction-rolls the piston will be forced toward the head of the cylinder, the air escaping through the check-valve o. So soon as the brakes are thrown on 25 as tight as desired the operator releases the brake-staff, and the pressure upon the outside of the piston P will hold the brakes in position until the valve o' is opened by pressing it inward and allowing the flow of air to 30 the cylinder to equalize the pressure upon both sides of the piston. The brakes are quickly thrown off so soon as they are released by the customary springs R, which are secured to the bottom of the car and exerts 35 their force in opposition to the draft of the board N. To allow the board to move smoothly, the journal n' traverses a slot in the upper end of the lever and the board passes through a guide-box k, which is secured upon the bar 40 K. The box is provided with a friction-roll k', as shown in dotted line, Fig. 1, upon which the lower side of the board N rests. In 45 the form of clamping device shown in Figs. 4 and 5 the forward end of the board N passes through a box S and rests upon a friction-roll journaled in the sides of the box. Within this box is journaled a cam s, the 50 journals of which project through the sides of the box, and the projecting ends are formed 55 square or angular to enter the arms of the bifurcated lever T. To the forward end of the lever T is jointed the treadle-rod t, upon which is fitted a cap t'. A rod t² is jointed underneath the forward end of the lever T 60 and passes down through the bottom of the box or hanger S. Around this rod is coiled a spring U, which exerts its pressure upwardly against the lever. When the brakes are thrown on and the board drawn forward, the 65 driver presses down upon the treadle-cap, depresses the lever T, partially rotates the cam s, and firmly clamps the board between the

cam and roller. The board may then be released from the friction exerted by rolls D H, thus preventing the wear which would be caused by the roll D and the strain upon the brake-levers. When the car comes to a stop, the driver releases the treadle, the lever T will be thrown up by the spring U, and the board released. 70

In the drawings the car is shown as running to the left. When the car is running in the opposite direction, the clamping device for holding the brakes on, which is in the rear of the car, is rendered inoperative. In 80 Fig. 1 this is accomplished by pressing the valve o² open and locking it in that position. In the form shown in Figs. 4 and 5 the treadle-cap may be removed to prevent the passengers from throwing on the holding device. 85

It will be seen from the foregoing that the essential features of my invention are in providing a smooth friction-roll to be secured upon and revolve with the car-axle, the draw bar or board connected to the brake-lever 90 and extending over said roll, and a movable friction device arranged above the axle-friction, and means connecting the upper friction and brake-staff, whereby the board is clamped between two friction devices and 95 carried forward by the momentum of the car to draw on the brakes.

The device shown for holding the brakes are not essential to the operation of the device above described, but are convenient to 100 prevent unnecessary wear upon the draw-bar and unnecessary strain upon the brakes.

I do not desire to be limited to the precise construction shown for forcing the board in frictional contact with the roll upon the axle, 105 nor to the means for holding the brakes on after the friction has been released, as these may be varied without departing from the spirit and scope of my invention; nor do I limit myself to the peculiar manner of securing the smooth friction-roll upon the axle or supporting the upper friction upon tubular extensions from it. 110

I have illustrated and described the best means known to me of embodying my invention in a practical operative form and shall claim that all equivalent means, although varying in form, are within the terms of my 115 claims.

What I claim is—

1. In a car-brake, the combination of a 120 brake-lever, a friction-pulley secured upon the car-axle, a draw-bar connected to the brake-lever and extending over the friction-pulley, a yoke journaled upon an eccentric, 125 the eccentric and an arm secured thereon to lower the yoke, friction-pulleys journaled in said yoke to press upon the draw-bar when the yoke is lowered, the brake-staff and connection between the brake-staff and yoke-actuating arm, whereby said draw-bar is pressed between said friction-rolls for the purpose 130 of throwing on the brakes, substantially as shown and described.

2. The combination, substantially as hereinbefore set forth, of the car brake and axle, the friction-pulley secured upon the axle and having extension-bearings d^3 , the standards 5 E, journaled upon said bearings, the eccentric F, journaled in the upper end of said bearings, the yoke G, carried by said eccentric, frictional rolls H, journaled in said yoke, the board N, connected to the brake-lever and 10 passing between the friction-roll upon the axle and said rolls H, the crank-arm F', secured upon the journal of the eccentric roll F, the brake-staff I, the rod i, and chain i', connecting said crank-arm and brake-staff.
- 15 3. The combination of the car-axles, the friction-pulley secured upon one of said axles to revolve therewith, standards E, clamped around the axle and carrying vertical moving friction-rolls and having a projecting lug 20 e, the box J, clamped around the opposite axle and having projecting lugs j, the bar K, secured upon the projecting lugs j and e, the hanger l', secured to said bar, the brake-lever L, fulcrumed upon said hanger, the brake-rods 25 M M', connecting the brakes and the lever, the board N, connected to the upper end of the brake-lever and passing between the friction-
- rolls, and means, such as shown, for forcing the frictions together, substantially as shown and described. 30
4. The combination, substantially as hereinbefore set forth, of the brakes and brake-lever, the board N, connected to the brake-lever, friction device connected by the car-axle and brake-staff to clamp said board and 35 draw on the brakes, and means, such as shown, to hold the brakes when the friction-rolls are separated. 35
5. The combination, as hereinbefore set forth, of the brakes, the brake-lever, the board N, connected to the brake-lever, the friction-rolls D H H for drawing the board forward, 40 the cylinder O and piston P fitted therein, the rod Q, connecting the board and piston, the outwardly-opening check-valve o and inwardly-opening spring-pressed valve o', valve-rod, and treadle-cap o² for opening the valve o' to release the brakes, substantially as 45 shown and described. 45
